UNITED STATES PATENT OFFICE

CHARLES A. UPSON, OF LOCKPORT, NEW YORK, ASSIGNOR TO THE UPSON COMPANY, OF LOCKPORT, NEW YORK, A CORPORATION OF NEW YORK

SHEET-CONVEYING APPARATUS

Application filed September 6, 1928. Serial No. 304,347.

My present invention relates to the manufacture and handling of sheets, boards, slabs and similar stock and particularly to the processing or treatment thereof wherein, in order to conserve space, the stock is conveyed back and forth in reverse directions between decks or levels arranged one above the other and it has for its object to provide a simple, convenient and efficient means for transferring the sheets or similar articles rapidly and safely from one deck to another. My improvements are directed particularly to means whereby a sheet is quickly transferred from an upper deck to the devices that carry it to the lower deck so that it will be reversed in direction in time to prevent succeeding sheets from interfering with its progress.

To these and other ends the invention resides in certain improvements and combinations of parts, all as will be hereinafter more fully described, the novel features being pointed out in the claims at the end of the specification.

In the drawings:

Fig. 1 is a side elevation of a wallboard making and processing machine in connection with which useful application of my invention may be made, the view being a fragmentary one of the front end of the machine;

Fig. 2 is a similar fragmentary view of the intermediate portion of the machine;

Fig. 3 is a similar fragmentary view of the delivery end of the machine;

Fig. 4 is an enlarged fragmentary longitudinal section through a portion of the drying oven of the machine shown in elevation in Fig. 3, the same being fitted with a conveyor and transfer means constructed in accordance with and illustrating one embodiment of my invention;

Fig. 5 is an enlarged detailed transverse section taken on the line 5—5 of Fig. 4;

Fig. 6 is an enlarged fragmentary section through certain driving mechanism taken on the line 6—6 of Fig. 4; and

Fig. 7 is a similar enlarged detail taken in section on the line 7—7 of Fig. 4.

Similar reference numerals throughout the several views indicate the same parts.

My present improvement may be utilized to advantage in connection with a machine for the manufacture of sheets or slabs such as that disclosed in my pending application for patent, filed January 12, 1928, Serial No. 246,345, and I have illustrated in Figs. 1, 2 and 3 so much of that machine as will be useful in understanding the purpose and effect of the present improvements. First referring briefly to these figures, it is to be understood as above explained that they collectively show the whole machine when placed end to end in the order named.

This particular machine is designed to produce as a continuous operation a continuously formed sheet or strip of wallboard such as is used as a building material, the outer faces thereof consisting of two paper liners enclosing between them a considerable body of mineral material. It is of no great concern herein as to what this material is beyond saying that it is a plastic mass which is fed between the liners while they are continuously moving. The liners referred to may be drawn from suitable supply rolls 1 and 2 and receive the plastic material between them from a hopper 3 as they pass around between rollers 4 arranged beneath the hopper. From these rollers the sheet is subjected to heat and pressure by passing through a long bed and between upper and lower heated platens 6 and 7. Emerging from the rear end of this platen section at 8, the strip is trimmed and slit at 9 and 10 and thence passes into a hardening oven 11 where it is partially dried and hardened or set sufficiently to pass between a set of drawing or feed rolls 12 which would otherwise injure it and which are located near the rear end of this hardening oven. The entire strip is drawn through the entire machine as thus far described by these drawing rolls and pushed by the latter upon what we will term the upper deck 13 of a long drying oven 14 that extends back beneath the hardening oven 11 and part of the platen bed 5—6 as shown. On this upper deck 13 which is conventionally shown in Fig. 3 the strip is cut into separate sheets by a suitable severing device 15 and from

100

thence travels in the manner hereinafter described as successive separate sheets.

Both the hardening oven 11 and the drying oven 14 are supplied with and heated by hot air or other gases which are introduced and discharged through various ducts 16 but an understanding of these is not necessary to the disclosure of the present invention.

After leaving the upper deck 13 the stock passes through an intermediate deck 16 on which it travels forwardly again the full length of the oven 14 at which point it is transferred to a bottom deck 17 to again traverse the oven rearwardly to its full length whereafter it issues as a finished product at the rear end of the machine. The two transfer points that are required for the shifting of the stock successively downward are indicated generally at A and B in the general views, whereas the delivery point at which it emerges as a finished product is indicated at C. The present invention, as before indicated, has to do with these transfer mechanisms and as they may be of the same construction at both of the points A and B they are shown in detail only at A as a description of one will suffice for both.

In Fig. 4 a sheet or a length of wallboard stock is shown on the upper deck 13 at D about to be delivered to transfer mechanism. This deck and the two lower decks 16 and 17 are composed in the present instance of a plurality of spaced parallel rolls 18 all driven in unison in the respective directions shown by the arrows at what we will call oven speed. The driving gear consists of sprockets 19 on the ends of the rolls with which mesh sprocket chains 20 driven from a suitable source of power. The upper or feeding deck 13 terminates in an inclined transfer element indicated generally at 21, which element also comprises a plurality of rollers 22 provided with sprockets 23 and driven by sprocket chains 24 suitably geared to turn these rolls at oven speed also. The element 21 is inclined downwardly and rearwardly in the direction of the transfer element 25 that is inclined downwardly and forwardly and passes under the rear or lower end of the element 21 and leads to the lower deck 16 as a continuation thereof.

The conveying rolls 26 of that portion of the transfer element 25 which extends beneath and beyond the lower end of the transfer element 21 from the point a forwardly are driven independently through sprockets 27 and sprocket chains 28 at greater speed than all of the other rolls or at greater than oven speed for which purpose a larger sprocket 29 is fixed to the shaft of one of the deck rolls 16 and drives one of the group of rolls 26 through a sprocket chain 30 and a small sprocket 31 on the shaft of that last mentioned roll. The purpose of this is as follows:

With all of the conveyor rolls moving in

the directions indicated by the arrows, with the exception of the independently driven group 26 on the transfer element 25, the board or stop sheet D passes from the deck 13 down the inclined transfer element 21 and is shoved out rearwardly to its full length on to the transfer roller 26 of the element 25. In doing so it momentarily avoids the group of rollers which are rotating at a greater speed in a reverse direction and contact and rides upon a group of idler rollers 32 at the far upper end of the transfer element 25, which rollers have intervening guide plates or deflectors 33 to prevent the board at its advancing edge from becoming locked against or beneath them. When the board has fully left the driven rolls of the upper transfer element 21 it falls upon the fast reversing rolls 26 of the lower transfer 25, as shown in Fig. 4, jointly with the idle rolls, so that the board is quickly reversed and hurried down the incline of the lower transfer to the lower deck 16 next below before the succeeding sheet or board travelling at the slower rate has had time to fall upon it. In other words, an advance sheet falls upon and is carried out of the way by the lower transfer element in a reverse direction beneath the succeeding sheet whereupon it assumes a rate of travel the same as the following sheets that are being fed from the making machine and the sheets ahead that have been reversed again by the similar mechanisms at D and are travelling through the oven toward the delivery point C. The working of the machine is thus made as rapid as possible and the sheets are so close together that the full capacity of the drying oven is utilized.

It is best that the work pieces D after being projected through the transfer incline 21 of deck 13 to the reverse transverse incline 25 of deck 16 on to the idle rolls 32 should be expedited as far as possible in falling also jointly upon the reversing speed rolls 26. In other words, it is important that the rear edge of the sheet of board should pass abruptly from transfer 21 to transfer 25. To effect this, I provide a roller 34 intermediately of the last roll 22 of the transfer 21 and the adjacent roll 27 of the lower transfer 25 between which two rolls there runs a rubber or similar apron 35 which may be continuous from side to side of the machine or may be divided into a plurality of spaced narrow belts as shown. With this construction it will be seen that as the rear edge of the sheet D leaves the last roller 22 of the upper transfer it will pass on to this belt or belts and have a continuous propelling contact therewith in the proper direction until the sheet falls squarely upon the lower transfer to be instantly propelled by the speed rollers 26 of the latter. The result is that there is practically no pause between the movement of the

sheet D in first one direction and then the other as it passes between the transfers and a succession of sheets may follow one another rapidly without interference.

5 I claim as my invention:

1. In a sheet processing machine for the continuous running of severed sheets of wall-board and similar stock, the combination with upper and lower superposed and substantially co-extensive decks for carrying the stock in reverse directions, of upper and lower transfers communicating with the respective decks, and means associated with the delivery end of the upper transfer for positively conveying a sheet of stock down upon the lower transfer.
- 10 2. In a sheet processing machine for the continuous running of severed sheets of wall-board and similar stock, the combination with upper and lower decks for carrying the stock in reverse directions, of upper and lower transfers communicating with the respective decks, said transfers each comprising a plurality of driven rolls, and means associated with the delivery end of the upper transfer for positively conveying the rearward edge of a sheet of stock down upon the lower transfer, said means comprising a roll arranged adjacent to the lower transfer and a belt
- 15 20 25 30 travelling on said roll and over the roll at the delivery end of the upper transfer.
